GASEOUS ELECTRIC DISCHARGE DEVICE

Eduard G. Dorgelo, Eindhoven, Netherlands, assignor to General Electric Company, a corporation of New York

Application April 30, 1935, Serial No. 19,086
In Germany May 3, 1934

2 Claims. (Cl. 176—122)

The present invention relates to gaseous electric discharge devices generally and more particularly the invention relates to such devices the containers of which are at an elevated temperature during the operation of the device, such as high pressure mercury vapor lamps and lamps the gaseous atmosphere of which consists of or comprises the vapor of a difficultly vaporizable metal, that is, a metal which is at a pressure of less than 1 mm. at a temperature of 200° C., such as sodium, cadmium, magnesium, or zinc.

I have observed that at the high container temperatures characteristic of such lamps during the operation thereof the glass wall of the container is electrically conducting and that, when an auxiliary electrode is mounted in contact with the container wall, electrolysis takes place at the contact points between the container and the auxiliary electrode. The current flowing through the container glass at the contact points softens the glass which terminates the life of the lamp.

The object of the present invention is to provide a long lived gaseous electric discharge lamp device the container of which is at an elevated temperature during the operation of the device and which container has an auxiliary electrode associated therewith. Still further objects and advantages attaching to the device and to its use and operation will be apparent to those skilled in the art from the following particular description.

The invention attains its object by interposing between the auxiliary electrode and the wall of the container a body of material which is a good electrical insulator even at the high container temperatures. In one embodiment of the invention at least the part of the auxiliary electrode in contact with the container wall is covered with an insulating enamel. When desired the auxiliary electrode consists of a metal the oxide of which is non-conducting even at elevated temperatures and the auxiliary electrode is oxidized at the part thereof in contact with the container wall.

In the drawing accompanying and forming part of this specification a gaseous electric discharge lamp device embodying the invention is shown in which—

Fig. 1 is a front elevational view of a gaseous electric discharge lamp device embodying the invention, and

Fig. 2 is a side, partly sectional view of the embodiment of the invention illustrated in Fig. 1.

Like numbers denote like parts in both the figures.

55 Referring to the drawing the new and novel

gaseous electric discharge lamp comprises a U-shaped container 1 having an electrode 2 sealed into each end thereof and having a gaseous atmosphere therein comprising starting gas, such as neon at a low pressure of approximately 1 to 5 20 mm., and a metal vapor, such as sodium vapor. A quantity of sodium is introduced into said container 1 during the manufacture of the lamp, which acts as the source of the sodium vapor. Said electrodes 2 are electron emitting when 10 heated and comprise a heater element, such as a coiled tungsten filament having another tungsten or nickel filament wrapped around said coiled filament, coated or impregnated with an electron emitting material, such as barium oxide. In 15 order to obtain an effective metal vapor pressure in the lamp during the operation thereof the container 1 must be at an elevated temperature. A heat conservator, such as a double-walled jacket having the space between the walls thereof evacuated, which reduces heat losses from said container 1 and in which said container 1 is removably mounted is useful in this connection.

The lamp has an auxiliary electrode consisting of an element 3, of nickel, for example, in contact with said container 1 at the curved part thereof and a narrow metal strip 4 extending along said container 1 between the parallel legs thereof. The element 3 partially surrounds the curved part of the container 1 and is covered 20 with an electrically insulating enamel layer 5, such as aluminium oxide or magnesium oxide, so that said element 3 is separated from the container 1. The strip 4 is connected to a current lead of one of the electrodes 2 so that the auxiliary electrode is at the same potential as the main electrode 2. When desired, the auxiliary electrode is at a different potential than said main electrode 2. When desired, the strip 4 is likewise covered with insulating enamel and is mounted 25 along the container 1. Softening of the container 1 at the parts thereof covered by the element 3 and the strip 4 does not take place in the above described lamp. When desired, the strip 4 and the element 3 consist of aluminium the surface of 30 which is oxidized.

While I have shown and described and have pointed out in the annexed claims certain novel features of the invention, it will be understood that various omissions, substitutions and changes 35 in the forms and details of the device illustrated and in its use and operation may be made by those skilled in the art without departing from the broad spirit and scope of the invention, for example, when desired, the element 3 is uncoated 40 and the strip 4 is uncoated. 45

and a sheet of mica is interposed between the element 3 and the container 1; when desired, the auxiliary electrode is a wire wound around the container which wire is covered with insulating material, and, when desired, the surface of the wire is oxidized and is of a material the oxide of which is insulating.

What I claim as new and desire to secure by Letters Patent of the United States, is:

10. 1. An electric discharge device comprising a U-shaped container, electrodes sealed therein at the ends thereof, a gaseous atmosphere therein, an external auxiliary electrode mounted on the

curved part of said container and a layer of insulating material interposed between said auxiliary electrode and said container.

2. An electric discharge device comprising a U-shaped container, electrodes and electrode leads sealed therein at the ends thereof, a gaseous atmosphere therein, an external auxiliary electrode mounted on the curved part of said container, a layer of insulating material interposed between said auxiliary electrode and said container and a current lead connecting said auxiliary electrode to one of said electrode leads.

EDUARD G. DORGELO.
